UNITED STATES PATENT OFFICE.

GEORGE ELDRED VAN FOSSEN, OF FREDERICK, MARYLAND, ASSIGNOR TO OX FIBRE
BRUSH COMPANY, A CORPORATION OF WEST VIRGINIA.

BRUSH MACHINE

Application filed March 17, 1921, Serial No. 452,958. Renewed September 27, 1923.

To all whom it may concern:

Be it known that I, GEORGE ELDRED VAN FOSSEN, citizen of the United States, and resident of Frederick, in the county of 5 Frederick and State of Maryland, have invented certain new and useful Improvements in Brush Machines, of which the following is a specification.

This invention relates to brush-machines, 10 having reference more particularly to the mechanism for aiding in forming the tufts and guiding them to the brush backs. A mechanism for this purpose is illustrated in Letters Patent of the United States No. 15 920,588, dated May 4, 1909, such patented mechanism comprising a tuft guide or casing mounted to swing in a vertical plane toward and from the brush back in timely relation to the vertical reciprocations of the tuft-inserting slide, the lower forward end of the guide or casing being provided with a toe or projection which, when the guide is swung downward into position for the tuft-inserting operation, pushes back the adjacent seated tuft 20 and provides a free passage for the new tuft to the brush back. Said patented mechanism permits the filling of the back in only one direction of movement of the latter, that is, from left to right or from 25 right to left, as the case may be.

The object of my invention is to provide simple and efficient mechanism which is operable to form the individual tufts and guide them to the brush back and also to 35 push out of the way of the entering tuft the previously-inserted tuft, irrespective of the direction of movement, to the right or to the left, of the brush back below the tuft inserting element.

40 To this end my invention comprises various novel features of construction and combinations of parts which will be hereinafter described and claimed.

In the drawings—

45 Figure 1 is a side elevation of a brush-machine embodying a preferred form of my invention, only so much of the machine being shown as is necessary to illustrate the improvements. In this view the tuft-guide is 50 illustrated in raised position on one side of the vertical.

Fig. 2 is a similar view, partly in section, showing the tuft-guide in its central or active position.

55 Fig. 3 is a sectional elevation of a por-

tion of the machine, as viewed from the side opposite to Figs. 1 and 2, the guide being shown in a raised position opposite to that shown in Fig. 1.

Fig. 4 is a side elevation, on an enlarged scale, of the tuft-guide and associated parts as shown in Fig. 3, but viewed from the opposite side of the machine.

Fig. 5 is a horizontal section through the reversing slide-bar and its accessories, as on the line 5—5 of Fig. 4.

Fig. 6 is a vertical section through the tuft-guide and its associated parts, the guide being shown in central position and the tuft-setting slide being illustrated in down position and with a tuft seated thereby in a brush block.

Fig. 7 is a perspective view of an oscillatory locking arm hereinafter described.

Fig. 8 is a horizontal section through the supporting structure, on a plane above the tuft-guide, as on the line 8—8 of Fig. 6.

Fig. 9 is a perspective view of the tuft-guide and its appurtenances.

Referring to the drawings, 10 designates the supporting frame; 11 the drive shaft of the machine, and 12 the fiber magazine. A single delivery magazine is shown; but, of course, a plural delivery magazine, and its appurtenances, such as described in Patent No. 920,588 aforesaid, may be employed.

13 designates a horizontal shaft which is driven from the drive shaft by means of a belt 14 passing around pulleys 15, 16 on the respective shafts.

17 designates one of the tables on which the blocks 18 to form the brush-backs are supported and by which they are fed to the boring and tuft-inserting devices. In the present instance, the table is illustrated as provided with holding devices for two oppositely-inclined adjacent brush blocks, so that one of the bored blocks may be conveniently in reserve while the other is being filled with tufts, as seen in Fig. 6.

19 designates the horizontally-reciprocatice slide by means of which quantities of fiber are successively separated from the mass in the magazine, and fed into position for insertion as tufts into the adjacent bored block on the table 17. The slide herein illustrated comprises generally a long bar having a suitably-disposed cut-out portion into which extends one end of a laterally insert piece 20 on the bar so as to provide a vertical

opening 21. The free end of the insert piece is formed with an overhanging lip 22 which is designed, as the slide is moved beneath the magazine, to engage a quantity of the overlying fiber and to force it down into the opening. A plate 23, which is slidably mounted on the bar, in advance of the opening, is provided with a forwardly-extending lip 24 adapted to close over and confine the gathered fiber within the opening when the plate is moved relatively to the bar, which plate is retracted from the opening 21 as the bar approaches the tuft-inserting devices. Through the bar is formed an opening 25 to permit the downward passage of the tuft by the inserting devices. Pivoted to one end of the bar is a link 26 which is connected through a spring-controlled frame 27 with a lever 28 in engagement with a cam 29 fast on the shaft 13, whereby the slide is longitudinally reciprocated to move its fiber-receiving portion 21 beneath the magazine and adjacent the tuft-inserting devices alternately.

30, 30' designate the vertically-reciprocati-
35 v slides which in each successive downward stroke are relatively operated to form a wire staple and in conjunction therewith to insert and secure a tuft of fiber in a hole 30 of the bored block. The mechanism for operating the slides includes a rock-lever 31 which is connected at its ends with the slides and with a crank-arm 32 on the shaft 13 by means of links 33, 34 respectively.

35 designates a lower horizontal shaft which is driven step-by-step through suitable connections actuated from the upper shaft 13 which connections include a ratchet wheel 35' fast on the shaft 35; a rock-arm 40 35² bearing a pawl 35³ in engagement with the ratchet wheel and an eccentric 35⁴ mounted on the shaft 13 and connected by means of a rod 35⁵ with the rock-arm. The shaft 35 carries a cam wheel, the peripheral cams 36 of which, through suitable transmitting devices, effect the requisite transverse, vertical and longitudinal movements of the work-holding tables in order to position the brush-blocks with respect to the 45 boring and tuft-inserting devices. The transmitting devices include a horizontally-reciprocati-
50 v frame 37 under the influence of the cams 36 and carrying a vertical pin 37¹ extending through a longitudinal guide structure 37² which is operatively connected with the brush table.

No detailed illustration or description of the various mechanisms above indicated is deemed necessary herein as such mechanisms are or may be of the character described in the Lebherz Patent No. 920,588 aforesaid, and also in the Young Patents Nos. 578,907 and 664,989 dated March 16, 1897, and January 1, 1901, respectively, referred to in the 55 said Lebherz patent.

The preferred form of mechanism embodying my present invention comprises a tapering tubular casing 38 of the general shape most clearly illustrated in Figs. 6 and 9. The vertical opening 39 of this 70 structure for the passage of the slides 30, 30' and the associated staple and fiber, is reduced from top to bottom so that the fiber, during its descent, is doubled into tuft form about the lower end of the slides. The base 75 of the structure is rounded as shown and is provided at its respective ends with oppositely-projecting toes 40. The casing is affixed to a bracket 41 which is fast on one end of a horizontal shaft 42 journaled in a suitably-disposed bearing bracket 43 on the main frame. On the opposite end of the shaft 42 is loosely mounted a rocker-arm 44 which is frictionally held in position on the shaft by means of a friction washer or cap 45 fastened to the end of the shaft so as to bear against the arm. Hence by actuation of the rocker-arm as hereinafter described the casing may be positioned vertically with its opening in axial alinement with the slides 30, 30' and may be oscillated on either side (right or left) of the vertical, as desired. The arm 44 is connected by means of a link 46 with one arm of a crank-lever 47 which is pivoted on the main frame, the other arm of the lever being held in operative contact with a cam 48 fast on the shaft 13, by means of a spring 49 which is secured at its ends to the lever and frame respectively. The contour of the cam 48 (Fig. 2) is such that the crank-lever 47 is oscillated to swing, through the link 46, the arm 44 in an arc from a vertical to a laterally-inclined position, the swing being either to the right or the left of the vertical, so that the leading toe or projection 40 will press back the opposing tuft in the block as may be required by the direction of motion of the brush-block, viz, from right to left or vice-versa. A vertical guide piece 50 affixed to the frame guides the horizontal arm of the crank-lever.

Fast on the body of the shaft 42 is a head having two oppositely-extending arms 51 which are adapted during the rotation of the shaft 42 to abut against the opposing frame plate 52, and thus limit the upward movement of the arms, and, perforce, the extent of rotation of the shaft, to the right or left as desired.

On the shaft 42 adjacent the hub of the rocker-arm 44 is an arm 53, termed a locking arm, having at its outer end a projection comprising a radial tooth 54 and a laterally projecting shoulder 55, the latter being arranged to overhang and contact with an arched cam surface 56 formed on the hub end of the arm 44, in such wise that the locking arm partakes of the oscillatory motion of the arm 44. The shoulder 55 bears upon

and has capacity for relative rocking movement on the cam surface 56 in such a manner that if the locking arm be rigidly held in up-standing vertical position the shoulder will bear upon one inclined face or the other of the cam surface 56 and thus tend to maintain the locking arm, together with the tuft-casing, in vertically-depending position.

- 10 A vertically-movable bifurcated plate 57 straddles the tooth of the arm 53, the inner edges 58 of the legs of the plate constituting cam surfaces which curve downwardly and outwardly from a central notch 58'. 15 adapted to receive the tooth 54, when the arm 53 is in vertical position. This plate 57 is guided at its vertical edges in spaced-apart guide bars 59 depending from the frame structure. The upper end of the plate 20 is connected by means of a link 60 with one arm of a rock-lever 61 which is pivoted on the main frame, the other arm of the lever bearing a roll 62 which is maintained in operative contact with a cam 63 on the shaft 25 13 by the action of a spring 64 which is secured at its ends to the lever and frame, respectively. (See Fig. 2). The contour of the cam 63 is such that when the arms 44, 53 are swung to vertical position the plate 20 57 is depressed to engage the notch 58' with the up-projecting tooth 54 of the arm 53 and thus centralize said latter arm and lock it in position. The contour of the lower portion of the cam edges 58 of the plate is 25 such as to permit the free rotation of the tooth 54, during the vertical movement of the plate, and the contour of the upper portion of the cam edges is such as to effect and insure the centralizing movement of the 30 tooth in respect to the notch 58'. In the descent of the horizontal arm of the crank-lever 47 above referred to to effect the downward swing of the arm 44 and the concurrent upward swing of the arm 53, such lever arm bears upon the shorter arms of a 35 pair of spaced-apart gravity crank-levers 65 which are pivoted on the guide bars 59, as at 66, the longer depending arms of said crank-levers thus being swung toward each 40 other. These longer arms are so disposed in spaced relation to each other that when they are swung inward they move into the path of travel of the radial tooth 54 of the rocker-arm 53 through the respective lateral arcs, that lever-arm adjacent the up-turning tooth bearing against the latter and insuring its movement beyond the projection 67 formed at the juncture of the upper and lower portions of the proximate cam edge 45 58. The levers 65 thus perform the function of a safety device. (See Fig. 2.)

On the lower ends of the depending members of the plate 57 are laterally projecting pressure blocks 67 for a purpose hereinafter explained.

During the step-by-step movement of the brush block from right to left or from left to right, below the inserting slide 30, whether the movement of the brush block be longitudinal or transverse of its major axis, as determined by the operation of the table, the relation of the tuft-casing and its co-operating parts is such that the casing swings in an arc to the right or to the left of the vertical, as the case may be. When the casing is locked in vertical position the fiber is driven down through the casing, bent into tuft-form, and inserted into the brush block. When the casing swings to the right or to the left, as the direction of movement of the brush block may dictate, the casing escapes the tuft thus seated, the block is advanced a step, and the casing is returned to vertical position preparatory to the insertion of a new tuft. In such return movement the leading toe 40 of the casing impinges against the previously inserted tuft and pushes it to one side so as to ensure a free unobstructed passage for the next succeeding tuft through the casing to the brush block, and so on.

An oscillatory plate 68 having in its upper edge a recess with oppositely-inclined ends constituting spaced-apart abutment shoulders 69, is pivoted, as at 71, to a horizontal slide bar 72 mounted in guides 73 on a pair of depending brackets 74. The guides are preferably provided with anti-friction rollers 75 for the slide-bar. The plate 68 is provided adjacent one end with an arcuate slot 76 into which freely extends from the bar 72 a pin 77 which co-acts with the respective ends of the slot to limit the extent of vertical oscillatory movement of the plate. This plate is preferably provided on one side, near its respective outer corners, with sockets 78, with opposite pairs of which spaced-apart spring-pressed locking pins 79 slidably supported in the bar are adapted to register, when the plate is in either inclined position, right or left, thus temporarily locking the plate in place. (See Figs. 4 and 5).

On the inner face of the plate 68, adjacent its respective ends, are two laterally-projecting studs or rolls 80, the spaced relation of which to the respective blocks 67 on the bifurcated locking plate 57 is such that when the bar 72 is in the right hand position shown in Figs. 1 and 2, the right hand block impinges against the opposing right hand stud 80 of the plate 68 and presses the adjacent end of the latter downward, thus throwing upward the left hand end of the plate 68 and positioning its left hand shoulder 69 in the path of rotation of the lower end of the rocker-arm 44, and that when the bar 72 is shifted to the left as shown in Fig. 4, the left hand block 67 impinges against the left hand stud 80 of

the plate 68 and reverses the angularity of the latter, thus positioning the right hand shoulder 69 in the path of rotation of the rocker-arm 44.

5 When the plate 68 is in the right-inclined position the link 46 is inclined downward to the right of the vertical, thus, by the movement of the crank-lever 47, swinging in an arc on the right-hand side and correspondingly oscillating the arms 44, 53, the shaft 42 and the tuft casing 38. In such position of the plate 68, its right hand shoulder 69 is below the path of the rocker-arm 44, thus permitting the motion of the latter. When, 10 13 however, the plate 68 is moved to the left and shifted to the left-inclined position as above described, the right hand shoulder 69 impinges against the opposing lower portion of the rocker-arm 44 and thus swings the latter to the left of the vertical. The link 20 thus being inclined downward to the left swings in an arc on the left-hand side and correspondingly oscillates the arms 44, 53, the shaft 42 and the tuft casing 38. In that 25 case the left hand shoulder 69 is below the path of the lower portion of the arm 44 so as to permit the free swinging motion of the latter. When the plate 68 is again moved to the right the right-hand operation of the 30 arm 44 and its appurtenances is repeated, and so on.

After the last tuft of each row has been inserted in the brush block, the bar 72 is shifted to the right or to the left as may be required by the next succeeding or return movement of the brush block; that is to say, when the block is moving from right to left the bar 72 is in the position indicated in Figs. 1 and 2; but upon the completion of 40 the row of tufts and preparatory to the movement of the block from left to right, the bar is shifted to the left as indicated in Fig. 4.

The reversing bar 72, as it may be called, is automatically shifted at predetermined 45 intervals by mechanism of the following character: One end of the bar is connected by means of a rod 81 to the upper arm of a lever 82 which is pivoted on a suitably-disposed bracket 83 on the main frame. A 50 spring 84 secured to the upper lever arm and to the adjacent bracket 83, tends normally to pull such arm and therewith the bar 72 to the right hand position illustrated in Figs. 1 and 2. The lower arm of the lever 82 is 55 jointed to the upper arm of a lower lever 85 also pivoted on the bracket 83. The lower arm of the latter lever 85 is jointed to a horizontal slide-bar 86 which is guided in a suitable bracket 87 arranged on the main frame and adjacent the shaft 35. On this shaft is 60 a wheel 88 provided with a cam 89 (or a series of spaced-apart similar cams) into the path of rotation of which extends a laterally projecting stud or roll 90 on the slide-bar

86, said cam being so formed and positioned 65 that as it rides against and passes the stud or roll 90 the bar 86 is forcibly retracted and then released. When the bar 86 is retracted the combined levers 82, 85 are swung in opposite directions to each other on their respective fulcra, against the action of the spring 84, similarly to a toggle-joint, thus pulling the reversing bar 72 to the left. When the cam passes the stud or roll 90 the 70 slide-bar 86 is released, but by means of 75 suitable locking mechanism such bar is maintained in retracted position until the next succeeding row of tufts has been formed and inserted in the brush back. The particular 80 locking mechanism herein illustrated comprises a latch lever having a hook-shaped arm 91 which is movable into and out of locking relation to a spud 92 on the bar 86. A spring 93 secured to the other arm 94 of the lever maintains the hook-shaped arm normally in the path of the spud 92, so that when the slide-bar 86 is retracted as above described, the spud passes under the hooked arm and is engaged thereby; the bar 86 thus being securely held in the retracted position. 90 The lever arm 94 is jointed to the lower arm of a vertical lever 95 which is pivoted, as at 96, on the bracket 87, the upstanding arm of the latter lever having a stud or roll 97 located in the path of rotation of a cam 98 (or a series of spaced apart similar cams) on the wheel 88. The cam 98 is arranged in spaced relation to the cam 89, so that at a predetermined interval after the retraction of the slide-bar 86 the cam 98 impinges 100 against the opposing stud or roll 90 and swings the upper arm of the lever forcibly to the right, thus moving the latch lever and disengaging its hooked end from the spud 92, whereupon the slide 86 resumes its 105 previous position to the right.

The general operation of the foregoing described tuft-inserting and guiding mechanisms may be briefly explained as follows:

The table for the bored blocks being supplied with blocks and being brought to a predetermined starting point for the filling of one of the blocks with tufts, the horizontally reciprocative slide 19 functions to take the required amount of fiber from the magazine 12 and carry it to a position for transference to the path of the vertically-reciprocative slides 30, 30', which latter, in their initial downward movement and prior to receiving the fiber, form a wire staple, which as it descends with the slides straddles the fiber and serves as a means to fasten the tuft in the block as usual. Simultaneously with the start of the vertical movement of the slides 30, 30' the cam 48 becomes operative and actuates the crank-lever 47 which, in turn, transmits its motion through the link 46, the rocker arm 44 and the shaft 42,

to the tuft casing 38 in such a manner as to position the casing vertically to receive the slide 30 and the fiber on its downward movement; the casing thus acting as a guide for 5 and means of doubling the fiber, and also acting to clear the adjacent previously inserted tuft from the path of the tuft being inserted. Coincidentally with the downward swing of the tuft casing the bifurcated plate 10 57 descends, being actuated by the cam 63, rock lever 61 and link 60. The motion of the plate is so timed that when the tuft casing is in the vertical position (as seen in Figs. 2 and 4), the central notch 58' of the 15 plate 57 engages the radial tooth 54 of the arm 53 and thus locks the arm and its adjuncts, including the casing, in that position; and the contours and relative position of the cams 48 and 63 are such that the tuft 20 casing and its actuating and locking mechanism are caused to remain stationary during the reciprocation of the tuft-inserting slide 30.

Upon the return of the slides 30, 30' to 25 their uppermost position the cams 63 and 48 again become active, the former cam causing the bifurcated plate 57 to ascend and thus release the tooth 54 of the arm 53, and the latter cam effecting the upward swing 30 of the tuft casing either to the right or left as required by the direction of travel of the brush block being filled. The upward movement of the casing clears it from the fiber of the tuft last inserted in the block and 35 allows the free movement of the work either longitudinally or transversely as the case may be, to bring the next adjacent hole in the block to the filling position. This done the above described cycle of operation is 40 repeated, and so on.

The direction of travel of the tuft-casing 38 which, on its upward movement, is away from the previously filled portion of the block, is controlled by the position of the 45 oscillatory plate 68, the function and operation of which, together with its associated parts, have been hereinbefore fully explained.

The track or travel of the brush block to 50 position its holes for the reception of the succeeding tufts may be varied as circumstances may require, and in accordance therewith the swing of the casing may be either longitudinal or transverse of the major axis 55 of the block, the casing operating to push previously inserted tufts clear from the path of the tuft which is being inserted regardless of the direction of travel of the block.

Although in the construction herein illustrated the tuft-casing is mounted to swing longitudinally of the normal plane of the brush block, it is obvious that the axis of oscillation of the casing can be changed in order to vary the path of motion of the cas-

ing; that is, the casing can be mounted to swing transversely of or in different angular relations to the normal plane of the brush block.

It is to be understood that I do not limit my invention to the particular construction 70 herein disclosed, as the mechanism can be modified in various respects within the principle of the invention and the scope of the appended claims.

I claim—

1. In a brush-machine having means for supporting and intermittently moving a brush block, a tuft-inserting device, and means for operating said device in relation to the block, a tuft-guide mounted for movement to position its delivery end at either side of the active path of the tuft-inserting device and adjacent the brush block, and mechanism for shifting the said guide to position its delivery end at either side of the tuft-inserting path, whereby the operative motion of the guide can be periodically reversed in accordance with the direction of movement of the brush block.

2. In a brush machine having means for supporting and intermittently moving a brush block, a tuft-inserting device, and means for operating said device in relation to the block, an oscillatory tuft-guide mounted to swing in an arc at either side of the active path of the tuft-inserting device and adjacent the brush-block, mechanism for oscillating said tuft-guide, and means whereby the said mechanism can be positioned at predetermined intervals to oscillate the tuft-guide through an arc on either side of said path.

3. In a brush-machine having means for supporting and intermittently moving a brush block, a tuft-inserting device, and means for operating said device, a tuft-guide mounted for movement to position its delivery end at either side of the active path of the tuft-inserting device and adjacent the brush block, mechanism for operating said guide, locking and releasing means for temporarily holding said guide in axial alignment with the tuft-inserting device, and means for shifting the said mechanism at predetermined intervals to operate the said guide to position its delivery end on one side or the other of the tuft-inserting path as desired, whereby the operative motion of the guide toward and from the inserted tufts in the brush block can be periodically varied in accordance with changes in the direction of movement of the block.

4. In a brush-machine having means for supporting and intermittently moving a brush block, a tuft-inserting device, and means for operating said device in relation to the block, a tubular tuft-guide having oppositely-extending lateral projections ad-

6
jacent its lower end, means pivotally supporting the upper end of said guide so that the lower end of the guide can swing toward and from the active path of the tuft-inserting device and adjacent the brush block, mechanism for oscillating said guide, and means whereby said mechanism can be positioned at predetermined intervals to oscillate the tuft-guide through an arc on either 10 side of said path in accordance with changes in the direction of movement of the block.

5. In a brush-machine having means for supporting and intermittently moving a brush block, a tuft-inserting device, and 15 means for operating said device in relation to the block, a tuft-guide, a shaft therefor, means, including a rock-arm, for oscillating said shaft, said arm having a frictional connection with the shaft, and means for periodically shifting said arm in relation to the shaft, whereby the shaft can be actuated to oscillate the tuft-guide through an arc 20 on either side of the active path of the tuft-inserting device in accordance with changes 25 in the direction of movement of the block.

6. In a brush-machine having means for supporting and intermittently moving a brush block, a tuft-inserting device, and 30 means for operating said device in relation to the block, a tuft-guide, a shaft therefor, means, including a rock-arm, for oscillating said shaft, said arm having a frictional connection with the shaft, means for periodically shifting said arm in relation to the shaft, whereby the shaft can be actuated to oscillate the tuft-guide through an arc on either side of the active path of the tuft-inserting device in accordance with changes 35 in the direction of movement of the block, and means for temporarily locking said tuft-guide in axial alinement with the tuft-inserting device.

7. In a brush-machine having means for supporting and intermittently moving a brush block, a tuft-inserting device, and means for operating said device in relation to the block, a tuft-guide, a shaft therefor, means, including a rock-arm, for oscillating 45 said shaft, said arm having a frictional connection with the shaft, means for periodically shifting said arm in relation to the shaft, whereby the shaft can be actuated to oscillate the tuft-guide through an arc on either side of the active path of the tuft-inserting device in accordance with changes 50 in the direction of movement of the block, a locking arm on said shaft, and a locking element movable into and out of engaging 55 relation with said locking arm when the tuft-guide is in axial alinement with the tuft-inserting device.

8. In a brush-machine having means for supporting and intermittently moving a brush block, a tuft-inserting device, and 60

means for operating said device in relation to the block, a tuft-guide, a shaft therefor, means, including a rock-arm, for oscillating said shaft, said arm having a frictional connection with the shaft, means for periodically shifting said arm in relation to the shaft, whereby the shaft can be actuated to oscillate the tuft-guide through an arc on either side of the active path of the tuft-inserting device in accordance with changes 70 in the direction of movement of the block, a locking arm mounted on said shaft and having a radial projection, a slide element having a centering notch adapted to receive said projection, and means for periodically reciprocating said slide element to move its notch into and out of engaging relation with said projection when the tuft-guide is in axial relation with the tuft-inserting device. 85

9. In a brush-machine having means for supporting and intermittently moving a brush block, a tuft-inserting device, and means for operating said device in relation to the block, a tuft-guide, a shaft therefor, 90 a rock-arm having a frictional connection with the shaft, a periodically movable lever, a link connecting said lever with the rock-arm, means for periodically shifting said arm in relation to the shaft, whereby 95 the shaft can be actuated to oscillate the tuft-guide through an arc on either side of the active path of the tuft-inserting device in accordance with changes in the direction of movement of the block, a locking arm mounted on said shaft and having a lock portion, a bifurcated slide element having a lock portion complementary to that of the locking arm and having cam edges diverging from the lock portion of the slide element, means for periodically reciprocating said slide element to move its locking portion into and out of engagement with that of the locking arm when the tuft-guide is in axial relation with the tuft-inserting device, and a pair of levers arranged in the path of the first-named lever and adapted to be actuated thereby to embrace the locking arm. 105

10. In a brush-machine having means for supporting and intermittently moving a brush block, a tuft-inserting device, and means for operating said device in relation to the block, a tuft-guide, a shaft therefor, a rock-arm having a frictional connection with the shaft, means, including a link connection, for oscillating said rock-arm, an oscillatory element having spaced-apart abutment portions, means for periodically tilting said element to move its abutment portions into and out of the path of the rock-arm in alternate succession, and means for longitudinally moving said element at predetermined intervals in such a manner that that abutment portions of the oscillatory 110 115 120 125 130 135 140 145 150 155 160 165 170 175 180 185 190 195 198

element alternately effect the shifting of the arm in relation to the said shaft, thereby causing the oscillation of the tuft-guide through an arc on either side of the active path of the tuft-inserting guide in accordance with changes in the direction of movement of the block.

11. In a brush-machine having means for supporting and intermittently moving a brush block, a tuft-inserting device, and means for operating said device in relation to the block, a tuft-guide, a shaft therefor, a rock-arm having a frictional connection with the shaft, means, including a link connection, for oscillating said rock-arm, an oscillatory element having spaced-apart abutment portions, means including a vertically-reciprocatve member, for periodically tilting said element to move its abutment portions into and out of the path of the rock-arm in alternate succession, and means for longitudinally moving said element at predetermined intervals in such a manner that the abutment portions of the oscillatory element alternately effect the shifting of the arm in relation to the said shaft, thereby causing the oscillation of the tuft-guide through an arc on either side of the active path of the tuft-inserting guide in accordance with changes in the direction of movement of the block.

12. In a brush-machine having means for supporting and intermittently moving a brush block, a tuft-inserting device, and means for operating said device in relation to the block, a tuft-guide, a shaft therefor, a rock-arm having a frictional connection with the shaft, means, including a link connection, for oscillating said rock-arm, an oscillatory element having spaced-apart abutment portions, a reciprocative slide to which said oscillatory element is pivoted,

means for periodically tilting said element to position its abutment portions in and out of the path of the rock-arm in alternate succession, means for normally holding said slide in one position, and means for periodically retracting and releasing said slide in such a manner that the abutment portions of the oscillatory element alternately effect the shifting of the rock-arm in relation to the said shaft, thereby causing the oscillation of the tuft-guide through an arc on either side of the active path of the tuft-inserting guide.

13. In a brush-machine having means for supporting and intermittently moving a brush block, a tuft-inserting device, and means for operating said device in relation to the block, a tuft-guide, a shaft therefor, a rock-arm having a frictional connection with the shaft, means, including a link connection, for oscillating said rock-arm, an oscillatory element having spaced-apart abutment portions, a reciprocative slide to which said oscillatory element is pivoted, means for periodically tilting said element to position its abutment portions in and out of the path of the rock-arm in alternate succession, means for normally holding said slide in one position, means for periodically retracting and releasing said slide, said last-named means including a reciprocative bar having a cam-engaging portion and a latch-engaging portion, connections between said bar and the slide, a latch device for said latch-engaging portion, and cam mechanism for alternately actuating said cam-engaging portion and said latch-device.

Signed at Frederick, in the county of Frederick and State of Maryland, this twelfth day of March A. D. 1921.

GEORGE ELDRED VAN FOSSEN.
